UNITED STATES PATENT OFFICE.

HUGH M. STOLLER, OF MOUNTAIN LAKES, NEW JERSEY, ASSIGNOR TO WESTERN ELECTRIC COMPANY, INCORPORATED, OF NEW YORK, N. Y., A CORPORATION OF NEW YORK.

DYNAMO-ELECTRIC MACHINE.

Application filed March 15, 1924. Serial No. 693,428.

To all whom it may concern:

Be it known that I, HUGH M. STOLLER, a citizen of the United States of America, residing at Mountain Lakes, in the county of Morris and State of New Jersey, have invented certain new and useful Improvements in Dynamo-Electric Machines, of which the following is a full, clear, concise, and exact description.

10 The present invention relates to dynamo-electric machines adapted to operate with alternating current.

A particular object of the invention is to provide for the operation of a plurality of 15 such machines in correspondence, when coupled only electrically and situated at any desired distance from one another.

The invention relates particularly to series wound machines, which are classed 20 as non-synchronous machines, and an object of the invention is to provide for operating two or more of such machines in step with one another both during acceleration and at synchronous or at running speeds.

25 A further object is to adapt such machines for use in simultaneous recording of pictures and sounds and to the simultaneous reproduction of pictures and sounds. In a known system of recording or of reproducing pictures and sounds simultaneously, the two kinds of recording (or reproducing) are effected by independent machines and it is essential to the production of the proper effects that the two machines be driven in 30 very close correspondence with each other.

It is also important to maintain proper absolute speeds in the recording and reproducing operations. A still further requirement is that both machines start to 40 produce in proper phase with each other so that not only is there a constant relation between the running of machines but there is also an exact coincidence in time between individual elements of the picture and 45 sound reproductions. One method of fulfilling this last requirement in accordance with the invention, is to start the machines at the same instant and to provide for both accelerating and running them in close step 50 with one another.

For this purpose it is desirable if not requisite to employ machines having positive starting characteristics, that is, each machine wherever located and whatever be 55 the nature of its load, must have sufficient

starting torque to begin operating as soon as the energizing circuit is closed. Series machines possess positive starting characteristics on account of the large flux density which they develop at zero or low speeds. 60 However, as mentioned above, series machines are non-synchronous and not only do not run in step with one another but their speed is subject to change with variations of either load or applied voltage. The invention enables series machines to be used for any situation where synchronous operation may be desired, and thus provides a system in which the positive starting characteristics above referred to are present and 65 in which, from the instant of starting, the machines run in substantially exact correspondence. The provisions by which these results are attained as well as the nature and object generally of the invention 70 will appear more fully from the following detailed description in connection with the accompanying drawings, in which—

Fig. 1 represents in schematic form one arrangement of associating a plurality of 75 series machines to run in close correspondence in accordance with the invention,

Fig. 2 is a similar representation of a preferred arrangement, and

Fig. 3 is a schematic diagram of one arrangement of the invention as applied to picture and sound recording and reproducing systems.

In Fig. 1 two series machines 1 and 2 are shown connected across the alternating current supply mains 3 and 4. Each machine comprises the usual field windings 5 and 6 and the rotating armature, the field windings being connected in series with the commutator brushes. Each machine is also provided with three slip rings as shown which are individually connected to respective points in the armature circuit separated by 120 electrical degrees from each other. If desired, a greater number than three slip rings could be used in which case the points of connection to the armature circuit would be distributed evenly around the armature. Brushes from the slip rings connect in the case of machine 1 to the three leads 7, 8 and 9, respectively and the corresponding brushes of machine 2 connect to the leads 10, 11 and 12, respectively. A three-pole switch 13 is adapted when closed to connect the lead 10 with the lead 7, the 105 110

lead 11 with the lead 8, and the lead 12 with the lead 9 so that respective points of the armature of each machine are connected with the corresponding points of the 5 armature of the other.

When power is applied to the supply mains 3 and 4 in any suitable manner and when the switch 13 is closed, the motors 1 and 2 will start from rest at substantially 10 the same instant and will accelerate together and thereafter be maintained in close step with each other regardless of variations in the load on either machine. As either machine tends to depart from the 15 in-phase position with respect to the other, a difference in voltage is set up between the points brought out from the respective armatures, so that a current flows between one machine and the other. This current is 20 of such sign that it will set up a torque depending in amount upon the departure of the machine from the in-phase position; the greater the departure, the greater being the torque. This torque therefore tends to 25 restore the machine to the in-phase position.

As stated hereinabove, series machines develop a large starting torque so that even though the machines 1 and 2 have different individual loads their series connection enables them to start practically at the same 30 instant. Also the armature voltages developed in starting are relatively large compared with those in other types of machines so that large differences of potential are produced when either machine gets out of step 35 with the other and hence the restoring amount is correspondingly large. It is found in practice that two or any desired number of machines connected in the manner shown in Fig. 1 can be made to accelerate in substantially absolute synchronism with each other and to maintain this synchronism after running speed is reached. 40

In Fig. 2 the machines 1 and 2 are substantially the same as in Fig. 1 except that each machine is provided with a fourth slip ring which is connected to a point in the armature circuit 180 electrical degrees from the point to which another of the rings is 45 connected. For example, the three slip rings in machine 1 of Fig. 2 corresponding to those of Fig. 1 are the rings which are brought out to the leads 7, 8 and 9 and the lead 14 connects to a point in the armature 50 circuit 180 electrical degrees from the point to which lead 9 is connected. Similarly in the case of machine 2, leads 10, 11 and 12 correspond with the similarly numbered leads of Fig. 1 and the lead 15 connects to 55 a point in the armature circuit 180 electrical degrees from the point to which lead 12 connects. When switch 16 is closed, therefore, a substantial short circuit is closed between leads 12 and 15 and another short circuit is closed between leads 9 and 14 so that 60

an independent shunt is connected across the armature circuit of each machine.

In operation the switch 13 of Fig. 2 is closed during starting and the switch 16 is opened. As described in connection with 70 Fig. 1 the machines 1 and 2 are electrically locked together when switch 13 is closed so that they are constrained to accelerate exactly in step with each other. When running speed is reached switch 16 is closed and 75 switch 13 may be opened. With switch 16 closed machines 1 and 2 remain series connected but, as stated, a short circuit is closed in each machine between points in the armature circuit substantially 180 electrical degrees, apart. This short circuit converts each machine into a series synchronous machine of the type described and claimed in the application of O. L. Dupy, Serial No. 699,438, filed March 15, 1924. As described 80 in Dupy's application, within certain voltage limits of the supply current, the series machine provided with a fixed armature shunt of this character maintains close synchronization with the supply current and since 85 each of the machines 1 and 2 is fed from the same supply mains 3 and 4, the two machines are independently maintained in synchronization with the supply current and therefore in synchronization with each other. 90

When machines 1 and 2 are employed for driving a picture and a sound reproducing mechanism respectively, it is found advantageous in order that both machines may start in exactly the same phase relation to 100 close switch 16 first and then to apply power to the leads 3 and 4 leaving the switch 13 closed. The fixed short circuit across the armature circuit of each machine prevents the machines from starting but causes them 105 to vibrate back and forth and finally to settle down to the same phase position. Switch 16 is then opened whereupon both machines begin to accelerate in step with each other. As described in the Dupy application referred to, switch 16 should be reclosed somewhat before the machines reach a speed corresponding to the lower limit of the voltage range within which they run in synchronization with the supply current in order 110 to avoid the chance of their attaining over-synchronous speed. 115

In Fig. 3 an arrangement is shown for securing the proper speed relations and the proper correspondence between the picture record and the sound record in both a recording and a reproducing system. Leads 3 and 4 supply preferably constant frequency alternating current to the switch 17. When the switch 17 is thrown to the left position 120 the recording mechanism including the motors 1 and 2 is energized, and when it is thrown to the right the reproducing mechanism including motors 1' and 2' are energized. Leads are brought out from each of 125 130

the motors to the respective switches 13 and 16, or 13' and 16' in the same manner as indicated in Fig. 2. The proper gear ratio is provided between the motors and the respective picture and sound recording and reproducing mechanisms. The motors 1 and 2 and the motors 1' and 2' may be identical with each other. In a system used by applicant a speed of 1200 revolutions per minute was assigned to each of these motors and the motors were six-pole 60 cycle machines.

In the operation for recording the switch 17 is thrown to the left, switch 16 is closed and switch 13 is closed. The motors 1 and 2 thereupon settle into the correspondingly same phase position for starting. It is understood, of course, that blank records have been placed in both the camera and the sound recorder. If now switch 16 is opened both motors 1 and 2 start to accelerate in step with each other and the picture record and sound record are advanced in exact correspondence from the points from which they started from the rest position. When the running speed has been reached, or slightly before, switch 16 is again closed. Switch 13 may be left closed but it is preferred to open it to prevent the transfer between machines 1 and 2 of any sudden im- pulses which may be set up by reactions upon the armature of either machine of mechanical vibrations in one or the other of the recording machines. For example, it is found in practice that slight irregularities may exist in the moving of the mechanical parts of the camera, and also of the projector when the record is being reproduced, which might be transmitted to the sound record, if the machines 1 and 2 were closely interlocked. By opening switch 13 however, and by employing independent synchronous circuits for the individual machines there is little or no tendency that such vibrations be transferred from one machine to the other. When the desired speed has been attained the recording operations may begin.

With switch 17 thrown to the right and with switches 13' and 16' closed the motors 1' and 2' in the reproducing system are brought into an exact in-phase position. Also the picture record that is to be used

for reproducing and the sound record are adjusted in their respective reproducing machines at some stated point by the aid of a mark on the record or some similar means. 55 Switch 16' is then opened whereupon both motors 1' and 2' advance exactly in step with each other. Before running speed is reached switch 16' is closed and when running speed is reached switch 13 is opened. 60 When the recorded pictures or sound vibrations on the respective records are reached the reproduction from each record takes place in exact time coincidence since both records were started from the proper position and were advanced to running speed exactly in step with each other.

What is claimed is:

1. In combination a plurality of series wound motors, alternating current supply 70 means common to said motors, means for establishing a plurality of direct connections between respective points in each armature circuit and corresponding points in another of the armature circuits of said machines for 75 starting, to cause said machines to accelerate in step with each other, and means for thereafter opening said direct connections and for closing independent short circuits across fixed points in each armature circuit 80 substantially 180 electrical degrees apart to cause said machines to run in synchronism with each other.

2. The method of operating a plurality of series alternating current motors in step 85 with each other comprising closing fixed short-circuits across the individual armature circuits of said motors when the motors are at rest, applying power to all of said motors simultaneously whereby said armatures take 90 up the same corresponding positions, and thereafter opening said short-circuits and closing direct connections from respective points in the armature circuit of each machine to the corresponding points in the 95 armature circuit of another of said motors, whereby said motors start, accelerate, and run in step with each other.

In witness whereof, I hereunto subscribe my name this 7th day of March A. D., 1924.

HUGH M. STOLLER.
